UNITED STATES PATENT OFFICE

DAVID H. VALENTINE, OF BROOKLYN, NEW YORK.

DUMPING-CAR.

SPECIFICATION forming part of Letters Patent No. 317,429, dated May 5, 1885.

Application filed February 24, 1885. (No model.)

To all whom it may concern:

Be it known that I, DAVID H. VALENTINE, of Brooklyn, in the county of Kings and State of New York, have invented a New and Improved Dumping-Car, of which the following is a full, clear, and exact description.

My invention relates to a new and improved dumping-car; and it consists of the construction, arrangement, and combination of parts, all as hereinafter described and claimed.

Reference is to be had to the accompanying drawings, forming part of this specification, in which similar letters of reference indicate corresponding parts in all the figures.

Figure 1 is a transverse sectional elevation of my new dumping-car, taken on the line *y y*, Fig. 2. Fig. 2 is a longitudinal sectional elevation taken on the line *x x* of Fig. 1; and Fig. 3 is a detail view of one of the bearing-plates and the body-supporting bar, the latter being in section.

The axles A A and wheels B B may be made of the usual form. The frame of the car is composed of the side pieces C C, that rest upon the axles A A, and the cross-pieces or boards D D, secured to and at the ends of the side pieces C C. The lower edges of the cross-pieces D D, reach near the rails R R of the track, so that in case of derailment of the car the boards D will rest upon the rails R and prevent the wheels B from coming in contact with the cross-ties T. A central draw-bar, E, parallel with the side pieces C, passes through openings made in the end-board D, to either end of which draw-bar other cars or an engine may be attached.

To the inner surfaces of the end-boards D are secured the heavy metal plates F, which reach above the upper edges of the end-boards D, and at their upper ends the plates F are notched, as shown at *f*, to receive the heavy bar G that supports the box or body H of the car, the hook portion *f'* of said notches serving to prevent the body of the truck from jumping out of its bearings when the said body is tilted for dumping. The upper edges of the end-boards D are inclined or beveled off, as shown at *d*, Fig. 1, to permit the box or body H to be tipped to one side for dumping.

The box or body H is composed of the bottom *h*, end boards *h' h'*, side boards *h²*, and hinged side-boards *h³*. At its corners it is pro-

vided with the posts *h⁴*, which have hooks *i* secured at their upper ends to permit the convenient attachment of ropes, chains, or hook, 55 to the body for lifting it and its load by a crane or otherwise from the truck, so that the load may be swung some distance from the truck and loaded or dumped, and the box or body returned to the truck. The notches *f* in the 60 plates F are made open for this purpose. The bar G that fits in the notches *f* and supports the body H upon the track is secured at its ends in the cross-pieces J J, secured to the bottom of the body or box H, and the bottom of the body is strengthened by the center piece, K, placed between the bottom *h* and the rod G, as shown clearly in the drawings, and the body is strengthened at the bottom along its edges by the side beams L L, as shown. The hinged 65 side piece *h³* may be locked in closed position by the bent rod M, the end *m* of which acts as a crank to turn the rod, so that the bent end *m'* may be turned to confine or release the said side piece, as will be understood from Fig. 1. 70 The draw-bar E of the truck is braced from the end braces D, by the braces *g g*, shown clearly in Fig. 2. By constructing the car as described it will be seen that the car need not be dumped alongside the truck, but may be 75 lifted from the truck of the car and swung by a crane to a spot some distance from the truck and there dumped, or the body may be loaded some distance from the truck and then lifted and swung back and replaced upon the truck, 80 which in various kinds of work will effect a great saving in time and labor. The car is also adapted for dumping directly from the truck 85 in the ordinary way.

Another advantage in making the body H 90 separable from the truck results from the fact that in case of accident the body will become detached from the truck and saved from destruction, and the truck being thus relieved of the weight of the body of the car will also, 95 in many cases, escape injury in accidents.

Having thus described my invention, what I claim as new, and desire to secure by Letters Patent, is—

1. In a dumping-car, the end-board D, provided with the notched or open bearing-plates F, in combination with the body H, having rod G, the upper edges of the boards D being beveled or inclined, as shown at *d*, whereby

the car may be dumped in the ordinary way or lifted from the truck and dumped at a distance, substantially as described.

2. The box or body H, provided with suitable posts and hooks and with the central rod, G, at the bottom, in combination with the end board D, provided with open bearing-plates for the rod G, substantially as and for the purposes set forth.

10 3. The cross-pieces D, placed in front and

rear of the wheels B, and framed into the truck and projecting below the other portion of the frame-work of the truck and adapted to rest upon the rails of the track in case of derailment of the car, substantially as described. 15
